UNITED STATES PATENT OFFICE.

GEORGE P. FINNIGAN, OF GREENE, NEW YORK.

NUT-LOCK.

SPECIFICATION forming part of Letters Patent No. 739,594, dated September 22, 1903.

Application filed March 25, 1903. Serial No. 149,455. (No model.)

To all whom it may concern:

Be it known that I, GEORGE P. FINNIGAN, a citizen of the United States, residing at Greene, Chenango county, New York, have invented 5 certain new and useful Improvements in Nut-Locks, of which the following is a full, clear, and exact description.

My invention relates to nut-locks, and has for its object the production of a simple and 10 effective lock for nuts particularly adapted for use where subject to jarring and vibration. I have shown it as used in connecting rails. It is obvious, however, that it may be useful in many other relations.

15 The following is a description of an embodiment of my invention, reference being had to the accompanying drawings, in which—

Figure 1 shows the same in perspective as used for connecting two rails together. Fig. 20 2 is a side elevation of the same. Fig. 3 is a view showing the parts in section on a line through the center of the nut. Fig. 4 is a section of the base or fish plate on the line x x. Fig. 5 is a perspective view of the key 25 or wedge. Fig. 6 is a perspective view of the nut.

Referring more particularly to the drawings, A A' are two rails, whose ends are connected by the perforated fish-plates B B', 30 through which pass the bolts C C C C, having nuts D D D D. The plate or base portion B' has formed upon it in proximity to the holes through which the nuts pass vertical projections E E E E. These projections 35 are not undercut, but are plain-faced, so as to be easily formed. When the nut is right-handed, these projections are preferably placed on the left of the holes, as shown—that is, at the reverse side of the nut. The 40 nuts themselves are undercut, as at f, parallel to their inner edges, so as to form recesses, in which a key G fits. This key is preferably angular, so as to extend into the recess on the top of the nut, as well as down the 45 side, and is firmly held in the recess by the projection E, acting to prevent the nut from unscrewing. Any tendency to unscrew results in an engagement of the nut with the plate or key G at the point H, thus locking 50 both the nut and key in position. In order to more completely insure the retention of the key G in place and take up looseness due to stretching of the metal fiber of the bolt, it is shaped so that it broadens toward the bot-

tom and has a bent or curved spring portion, 55 as at I, so that it expands to take up any loose play.

The construction constitutes a nut-lock which is simple and effective, as well as easily applied and inexpensive. 60

What I claim is—

1. In a nut-lock, the combination of a perforated base portion having a projection formed thereon, a bolt passing through the same, a screw-threaded nut thereon having 65 an undercut parallel to its inner edge and a key interposed in said recess and bearing against said projection and having a curved spring portion between said nut and said base portion, said spring being held compressed by said nut.

2. In a nut-lock, the combination of a perforated base portion having a vertical plain-faced projection formed thereon, a bolt passing through the same, a screw-threaded nut 75 thereon having an undercut parallel to its inner edge and a key interposed in said recess and bearing against said projection and fitting in the undercut on the top of said nut.

3. In a nut-lock, the combination of a perforated base-plate B' having a projection E, 80 a bolt C having a nut D with an undercut f, in combination with a key G having a curved spring portion and fitting in said undercut f and bearing against said projection, said spring being held compressed by said nut.

4. In a nut-lock the combination of a base-plate, a bolt passing through the same, a nut thereon having an undercut recess parallel to its inner edge, said plate having a projection with a plain vertical face and an L-shaped key between said nut and said projection, said key having its lateral projection extending over the top of said nut. 90

5. In a nut-lock, the combination of a perforated base-plate B' having a projection E, 95 a bolt C having a nut D with an undercut f, in combination with a dovetailed key G having a curved spring portion and fitting in said undercut f and bearing against said projection, said spring being held compressed by said nut.

Signed at Greene, New York, this 19th day of March, 1903.

GEORGE P. FINNIGAN.
